BALL GAME TARGET

Roy E. Munson, 133 Pine St., Ace, Tex. 77326

Filed Sept. 21, 1973, Ser. No. 399,323

Term of patent 14 years

Int. Cl. D21—01

U.S. Cl. D34—5 PP

FIG. 1 is a front elevational view of a ball game target, showing my new design;

FIG. 2 is a top plan thereof; and

FIG. 3 is a bottom view thereof.

I claim:

The ornamental design for a ball game target, substantially as shown.
